UNITED STATES PATENT OFFICE

WILLIAM FRANKLIN WILLIAMSON, OF SEARCY, ARKANSAS

DESIGN FOR A SMOKING STAND

Application filed February 11, 1933. Serial No. 47,220. Term of patent 3½ years.

To all whom it may concern:

Be it known that I, WILLIAM FRANKLIN WILLIAMSON, a citizen of the United States, residing at Searcy, in the county of White and State of Arkansas, have invented a new, original, and ornamental Design for Smoking Stands, of which the following is a specification, reference being had to the accompanying drawing, forming part thereof.

I claim:

The ornamental design for a smoking stand as shown.

WILLIAM FRANKLIN WILLIAMSON.
